UNITED STATES PATENT OFFICE.

EMANUEL S. MUMMA, OF ROCK HILL, PENNSYLVANIA.

STOVE ATTACHMENT FOR AUTOMOBILES.

1,140,055.

Specification of Letters Patent. Patented May 18, 1915.

Application filed March 12, 1914. Serial No. 824,309.

To all whom it may concern:

Be it known that I, EMANUEL S. MUMMA, a citizen of the United States, residing at Rock Hill, in the county of Lancaster and State of Pennsylvania, have invented certain new and useful Improvements in Stove Attachments for Automobiles, of which the following is a specification, reference being had therein to the accompanying drawing.

10 This invention relates to a vapor stove that may be attached to a permanent equipment of an automobile for the use of tourists or campers, and on which a certain amount of cooking may be done.

15 The object of the invention is to provide a stove using gasoline as fuel, which may be readily attached to the running board of an automobile, and that when not in use will in no way obstruct or interfere with the 20 usual use of the running board.

With these and other objects in view, my invention consists in certain construction and combination of parts as will hereinafter be fully described and claimed in the annexed specification, and illustrated in the accompanying drawings which form a part of this application, and in which like figures of reference refer to corresponding parts in all of the views; but it is fully understood that while I have here described my invention as shown, that I do not confine myself to the exact design, as slight changes may be made in the construction and arrangement of the several parts without departing from the spirit of the invention.

In the drawings: Figure 1, is the partial side view of an automobile, showing the application of the device. Fig. 2, is a detail 40 top plan view of the stove.

Referring to the drawing the device comprises one or more burners 10, which are mounted in the running-board 11, and fed by the pipe 12, leading from the fuel tank 13, to the automobile; the flow of fuel being 45 controlled by a cut off 14.

When not in use the burners 10, are protected and covered by a lid 15, properly protected by asbestos, and designed, when the stove is in use to be turned back against the 50 side of the automobile, as shown in Fig. 1, to protect the side thereof from the heat of the stove; and when in a closed position affording a step of the same level as the running board.

55 It is fully understood that the device may be secured to the running-board above or below the same, or may be built into it as a permanent fixture, or the device may be attached to some other convenient part of 60 the automobile.

Having thus described my invention what I claim as new, and desire to secure by Letters Patent is:—

A combined automobile running board 65 and stove, comprising a running board having a cut away portion hinged on one edge, and forming the cover of the stove, a stove member secured to the ends of the running board adjacent the cut out portion and under the same, and means for supplying fuel to said stove.

70 In testimony whereof I affix my signature in presence of two witnesses.

EMANUEL S. MUMMA.
